COLONIC THERAPY APPARATUS

Filed Dec. 20, 1928

UNITED STATES PATENT OFFICE

EMMA ADAMSON, OF DENVER, COLORADO

COLONIC THERAPY APPARATUS

Application filed December 20, 1928. Serial No. 227,257.

This invention relates to colon irrigation apparatus, for use in colonic therapy and has for its principal object the provision of a simple and efficient unit, in which adjustable 5 leg and foot supports, irrigation apparatus, and suitable water supply and drainage facilities will be conveniently combined.

Another object of the invention is to so construct the apparatus that the flow of the solution to the patient and the discharging fluids will be constantly in view of the operator.

Still another object is to provide convenient means for regulating the pressure, temperature and content of the treatment solution.

15 A further object is to provide a sanitary method of disposing of all waste and discharged solution.

A still further object is to provide means for supporting a suitable cover or curtain so 20 that the patient will be entirely concealed from view during the operation.

Other objects and advantages reside in the detail construction of the invention, which is designed for simplicity, economy, and efficiency. These will become more apparent 25 from the following description.

In the following detailed description of the invention reference is had to the accompanying drawing which forms a part hereof.

30 Like numerals refer to like parts in the drawing and throughout the description.

The drawing illustrates a perspective view of the complete invention.

The invention comprises a drainage tank 35 10, supported from the floor on suitable legs 11 and provided with a drain pipe 55. The apparatus is placed adjacent an operating table such as indicated in broken line at 53 which should substantially align with the front edge of the tank 10. Extending above the tank 10, is a rear splash hood 12 and a side splash plate 13. Within the splash hood 12 two vertical, tubular supports 14 and 15 are secured, separated by a cross bar 16. A 40 foot rest extends between vertically slidable fittings 17 on the tubular supports 14 and 15. The fittings 17 can be locked in any desired vertical position by means of set screws 18, so that the height of the foot rest 16 can be 45 varied as desired.

For the use of children an auxiliary foot rest frame 19 is provided. The auxiliary foot rest frame is carried from a pair of horizontal supporting bars 20 which slide within fittings 21 on the vertical standards 14 and 55 15. The fittings 21 are provided with clamp screws 22 by means of which the bars 20 can be locked in any desired horizontal position. A foot rest 23 extends between the side bar of the frame 19 and can be locked in any desired vertical position by means of set screws 24.

The support 15 terminates above the splash hood 12 in a terminal nut 25 which holds a curtain hook 26 in place. The support 14 is 65 provided with a similar curtain hook 27 and terminates above the splash hood 12 in a clamping T 28, provided with a suitable clamp screw 29. A hooked standard 30 slides within the T 28 and into the support 14. 70 The standard 30 can be secured at any desired height by means of the clamp screw 29.

The standard 30 supports a percolator 31 by means of a bale 34. The percolator 31 is closed by a cap 33 provided with a hinged 75 door 32, through which medicines and chemicals may be introduced into the percolator. A suitable thermometer 35 can be carried by the cap 33 to indicate the temperature of the solution in the percolator.

Water is fed to the percolator 31 through a supply tube 36 from a suitable mixing valve 37. The mixing valve 37 is fed from hot and cold water pipes 38 which extend into the tank 10 and terminate in any of the usual 85 faucets on the interior thereof to provide convenient means for flushing the tank.

A shelf 39 is hinged at 40 on a supporting bracket 41 extending from the side of the tank 10. The shelf 39 carries a clamp 42 90 which holds a glass Y-shaped connection tube 43 in place thereon.

The treatment solution is fed from the percolator 31 through a feed tube 44, which extends to a compression bulb 45 thence to one of the legs of the Y-shaped tube. A suitable shut-off 46 is provided to control the flow through the tube 44. A discharge tube 47 extends from the other leg of the Y-shaped tube 43 and discharges into the tank 10, con- 95 100

trolled by a suitable shut-off 48. A colon tube 49 extends from the stem of the Y-shaped tube 43.

At the side of the splash hood 12, brackets 50 are secured for attaching a pan rod 51 to support any desired pan 52 for the reception of instruments, bottles, etc., which are desired within reach of the operator.

In use, the shut-off 46 is first closed. The 10 desired amount of water is fed into the percolator 31 through the supply tube 36, the temperature of the water being controlled by the mixing valve 37 and the thermometer 35. If any medicines are to be used in the particular operation they are then placed in the solution in the percolator through the hinged door 34.

The patient is placed upon his back upon the operating table 53 with the anus extending slightly over the edge of the tank 10. If 20 the patient is an adult, the entire frame 19 is removed from the apparatus and the patient's feet are placed either upon the cross rod 54 or the foot rest 16. If it is desired to 25 elevate the feet to facilitate the operation the set screws 18 are loosened and the foot rest 16 is raised to the desired position when it can again be clamped in place by means of the screws 18. A suitable curtain can then 30 be placed over the patient and the entire apparatus and secured on the hooks 26 and 27.

The colon tube 49 is now inserted, the shut-off 48 is closed, and the shut-off 46 is opened. The operator can now observe the flow of the 35 solution, from the percolator 31 into the patient, through the glass Y-tube 43. If a stoppage of the flow is noted, pressure can be applied by hand through the medium of the compression bulb 45, to loosen the obstruction. Additional pressure can be obtained, 40 if necessary, by closing the shut-off 46 before operating the compression bulb 45. The operating pressure can be adjusted by varying the extension of the standard 30.

45 After the desired amount of solution has been used the shut-off 46 is closed and the shut-off 48 is opened to allow the solution to flow from the patient back through the Y-tube 43 and discharge into the tank 10 through the discharge hose 47. The nature 50 of the discharge can be observed by the operator through the glass Y-tube 43 so that a diagnosis can be made as to the treatment requirements. If necessary, the flow can be 55 stopped for this purpose by closing the shut-off 48.

If an extreme elevated position of the lower limbs is desired or if the patient is a child of small stature, the frame 19 is secured in 60 place within the fittings 21. The frame 19 can then be moved toward the patient and secured by means of the clamp screws 22 to force the knees upwardly over the body, or the rod 23 can be raised to elevate the patient's feet as desired.

The shelf 39 can be swung upon its hinge 40 to a vertical position alongside the bracket 41 so as not to interfere with placing the patient in position. The clamp 42 will prevent the Y-tube 43 from falling from the shelf 70 when in the tilted position.

It will be noted that by the arrangement of this apparatus the patient can be entirely covered; the scattering or spilling of solutions and discharges is entirely prevented; 75 and the nature of the discharge as well as the action of the solution is constantly in view of the operator, yet all discharging material is entirely enclosed for the operator's protection.

80 While a specific form of the improvement has been described and illustrated herein, it is desired to be understood that the same may be varied, within the scope of the appended claims, without departing from the spirit of 85 the invention.

Having thus described the invention, what I claim and desire secured by Letters Patent is:—

1. Colon irrigation apparatus comprising: 90 an open topped tank; a splash hood extending upwardly from said tank; standards vertically arranged within said splash hood; and a foot rest supported between said standards and arranged for vertical adjustment 95 thereon; and a foot rest frame supported by and extending forwardly from said standards, said foot rest frame being horizontally adjustable from said standards.

2. Colon irrigation apparatus comprising: 100 an open topped tank; a splash hood extending upwardly from said tank; standards vertically arranged within said splash hood; a foot rest supported between said standards and arranged for vertical adjustment thereon; 105 a foot rest frame supported by and extending forwardly from said standards, said foot rest frame being horizontally adjustable from said standards; and a second foot rest arranged for vertical adjustment in said foot 110 rest frame.

3. Colon irrigation apparatus comprising: 115 an open topped tank; a standard extending above said tank; a container carried by said standard; a conduit for supplying fluid to said container; a second conduit for discharging fluid from said container; a shelf supported from said tank; a transparent Y-tube carried by said shelf and connecting with said conduit; a third conduit from said Y-tube 120 and adapted to discharge in said tank; a colon tube extending from the third arm of said Y-tube; and independent valving means for said second and third conduits.

4. Colon irrigation apparatus comprising: 125 an open topped tank; a standard extending above said tank; a container carried by said standard; a conduit for supplying fluid to said container; a second conduit for discharging fluid from said container; a shelf 130

supported from said tank; a transparent Y-
tube carried by said shelf and connecting with
said conduit; a third conduit from said Y-tube
and adapted to discharge in said tank; a colon
tube extending from the third arm of said
5 Y-tube; independent valving means for said
second and third conduits; and a compression
bulb in circuit in said second conduit.

5. Colon irrigation apparatus comprising:
10 an open topped tank; a standard extending
above said tank; a container carried by said
standard; a conduit for supplying fluid to
said container; a second conduit for discharging
fluid from said container; a shelf sup-
15 ported from said tank; a transparent Y-tube
carried by said shelf and connecting with
said conduit; a third conduit from said Y-
tube and adapted to discharge in said tank; a colon
tube extending from the third arm of
20 said Y-tube; and a hinge for said shelf so
as to allow it to be swung to a vertical posi-
tion.

6. Colon irrigation apparatus comprising:
25 an open topped tank; a splash hood extend-
ing upwardly from said tank; standards ver-
tically arranged within said splash hood; a
foot rest supported between said standards
and arranged for vertical adjustment there-
30 on; a rod extending from within one of said
standards and terminating above said tank;
means for locking said rod at any desired
vertical height; a container supported by said
rod; means for supplying fluid to said con-
35 tainer; a colon tube; and means for discharg-
ing fluid from said container either into said
colon tube or into said tank as desired.

7. Colon irrigation apparatus comprising:
40 an open topped tank; means for supplying
water to said tank; means for discharging
water from said tank; a splash hood extend-
ing rearwardly and upwardly from the back
of said back; vertical standards secured to
45 and extending between the top and bottom
of said splash hood; slideable fittings carried
by said standards; locking screws arranged
to secure said fittings at any desired height
upon said standards; a foot rest bar extend-
50 ing between said fittings; and fixed fittings
carried by said standard; horizontal bars
slideable within said fixed fittings; means for
locking said horizontal bars in said fixed fit-
tings; and an auxiliary foot rest frame car-
55 ried by said horizontal bars; uprights in said
auxiliary foot rest frame; fittings vertically
slideable upon said uprights; and a second foot
rest bar extending between said second fit-
tings.

8. Colon irrigation apparatus comprising:
60 an open topped tank; a splash hood extending
upwardly from said tank; standards verti-
cally arranged within said splash hood; and
a foot rest supported between said stand-
ards and arranged for vertical adjustment
65 thereon; and hooks secured on said splash

hood and adapted to maintain a covering
over said tank.

9. Colon irrigation apparatus comprising:
70 an open topped tank; a standard extending
above said tank; a container carried by said
standard; a conduit for supplying fluid to
said container; a second conduit for dis-
charging fluid from said container; a shelf
75 supported from said tank; a transparent Y-
tube carried by said shelf and connecting with
said conduit; a third conduit from said Y-
tube and adapted to discharge in said tank;
and a colon tube extending from the third arm
80 of said Y-tube; and a clamp arranged to
secure said Y-tube to said shelf.

In testimony whereof, I affix my signature.
EMMA ADAMSON.
